UNITED STATES PATENT OFFICE.

THOMAS F. JOHNSON, OF NEW BRIGHTON, PENNSYLVANIA.

DESIGN FOR A GAGE.

SPECIFICATION forming part of Design No. 32,156, dated January 30, 1900.

Application filed December 7, 1899. Serial No. 739,579. Term of patent 14 years.

To all whom it may concern:

Be it known that I, THOMAS F. JOHNSON, a citizen of the United States of America, residing at New Brighton, in the county of Beaver and State of Pennsylvania, have invented a certain new and useful Design in Gages, of which the following is a specification, reference being had therein to the accompanying drawings.

This invention relates to a certain new and novel design for gages.

The invention consists of a gage which is triangular in form, as shown.

The invention has distinct features; and it consists of the novel outline to be hereinafter more particularly described.

In describing the invention in detail reference is had to the accompanying drawings, forming a part of this specification, and where like numerals of reference indicate corresponding parts throughout the several views, and in which—

Figure 1 is a perspective view of the gage. Fig. 2 is a top plan view thereof. Fig. 3 is a side elevation of the same.

The body portion of the gage is built up of three webs or strips 1, which come to a common center 2, one of the webs being provided with V-shaped openings 3 3, and another web is provided with a scale or graduations 4. The 30 web formed with the V-shaped openings is also provided with an inclined side 5. Another web is also provided with a V-shaped opening 6.

It will be noted that this gage is symmetrical in general form and presents a pleasing appearance to the eye.

Having thus described my new and original design, what I claim is—

The design for a gage, substantially as hereinafter shown and described.

In testimony whereof I affix my signature in the presence of two witnesses.

THOMAS F. JOHNSON.
